HAIR WAVING APPARATUS

Ralph M. Keele, San Francisco, Calif., assignor to
 Duart Manufacturing Co. Ltd., San Francisco,
 Calif., a corporation of California

Application March 14, 1932, Serial No. 598,542

3 Claims. (Cl. 132—36)

This invention relates generally to apparatus for the waving of human hair, such as are adapted for use in professional beauty parlors.

At the present time practically all hair waving methods and apparatuses in common usage fall into two general types, termed "spiral" and "croquignole". In spiral waving a pencil-like curling rod or mandrel is employed, and a strand of hair is wound about this rod in the form of a helicoid, beginning with the base of the strand and winding towards the tip. After the hair strand has been wound upon the rod, the wound hair is covered with a suitable absorbent pad, containing a vaporizable solution, and a tubular electrical heater is slipped over the assembly. The subsequent heating or cooking period renders the wave permanent. Spiral waving is subject to the following disadvantages:—It requires a highly skilled operator to secure uniformly good results, considerable time is required to wind the strand upon the curling rod preparatory to the heating operation, comparatively long heating periods are required at relatively high temperatures, and the resulting wave tends to be kinky and lacks a life-like appearance. In croquignole waving a two-part clamp is engaged with a flat hair strand, adjacent the scalp. The extending flat strand of hair is then wound upon a curler or mandrel, beginning with the tip of the strand and winding towards the protector. During this winding the convolutions are applied one on top of the other. After all of the strand has been wound upon the curler, the curler is mounted upon the protector, and then by further turning the curler, the wound hair is placed under tension. Ratcheting or clutching means is usually provided to prevent unwinding movement of the curler.

After the strand has been wound and tensioned, a pad containing a suitable vaporizable solution is placed over the curler and an electrical heater clipped over the assembly. While croquignole waving tends to produce a more natural wave, it is also subject to many inherent disadvantages. For example, it is difficult to secure uniform tension throughout the length of the strand, even though considerable torque is applied to the curler after being mounted upon the protector. As in spiral apparatus, a relatively long heating or cooking period is required at relatively high temperatures, due to the fact that the heat does not readily penetrate the several superposed convolutions of hair. Likewise the final tightening operation preparatory to heating the wound strand actually stretches the hair a con-

siderable amount, and frequently applies a direct pull upon the scalp if certain individual hairs may not be securely gripped by the protector.

It is an object of the present invention to devise a hair waving apparatus which will be of 5 a distinctly new and different type, and will obviate the disadvantages inherent in prior spiral and croquignole equipment.

It is a further more specific object of the invention to devise an improved hair waving apparatus which will enable waving a head of hair in a minimum of time, without discomfort to the subject whose hair is being waved, and with uniformly good results.

Further objects of the invention, relating for 15 example to simplicity of construction, and ease of manufacture and assembly, will appear from the following description in which the preferred embodiments of the invention are set forth in detail in conjunction with the accompanying 20 drawings. It is to be noted that the appended claims are to be accorded a range of equivalents consistent with the state of the prior art.

Referring to the drawings:

Fig. 1 is a side elevational view, illustrating 25 apparatus incorporating the present invention, to which a strand of hair to be waved has been applied.

Fig. 2 is a view of the apparatus illustrated in Fig. 1, but looking towards the other side of the 30 apparatus.

Fig. 3 is a cross sectional detail taken along the line 3—3 of Fig. 1.

Fig. 4 is a cross sectional detail taken along the line 4—4 of Fig. 3. 35

Fig. 5 is a cross sectional detail taken along the line 5—5 of Fig. 3.

Fig. 6 is a plan view looking down upon the apparatus illustrated in Figs. 1 and 2.

Fig. 7 is a transverse cross sectional view taken 40 along the line 7—7 of Fig. 6.

Fig. 8 is a detail illustrating the construction of a suitable clamp for engaging the hair strand, such as is incorporated with my apparatus.

Fig. 9 is a side elevational view of a suitable 45 tool to facilitate use of my apparatus.

Fig. 10 is a side elevational view in transverse cross section, illustrating a suitable heater for use with my apparatus.

Fig. 11 is an assembled view in side elevation, illustrating the heater of Fig. 10 applied to the apparatus of Figs. 1 and 2. 50

Fig. 12 is a cross sectional detail taken along the line 12—12 of Fig. 11. 55

Fig. 13 is a plan view of the heater illustrated in Fig. 10.

Fig. 14 is a plan detail illustrating the preferred construction of the absorbent pads utilized with my apparatus.

Fig. 15 is a side elevational detail, illustrating the means utilized for securing the absorbent pads to certain parts of the electrical heater.

Figs. 16, 17 and 18 illustrate diagrammatically the manner in which a hair strand is disposed upon my apparatus.

Referring first to Figs. 1 to 8 inclusive, one suitable embodiment of the apparatus consists of a frame designated generally at 10. Carried by this frame are a plurality of individual mandrel-like forms which have been designated 11 to 17 inclusive and 21 to 27 inclusive. As will be presently explained the number of individual forms utilized may vary, depending largely upon the length of the hair strand to be waved. While all of the forms may be identical in construction, they have been designated separately to facilitate explanation of manipulation of the device which will presently follow.

For the sake of lightness and cheapness of manufacture, each mandrel-like form is preferably hollow and in the form of a metal tube, having the major portion of its length substantially circular in cross sectional contour. A suitable detailed construction is illustrated in Figs. 3 to 5 inclusive, in which the mandrels 17 and 26 appear. One end portion of each mandrel is preferably flared or bellied as indicated at 31, the contour of this flared portion being preferably rectangular as shown in Fig. 1. Fixed within the other end portion of each mandrel there is a metal plug 32, for the purpose of assisting in the connection between the mandrels and the frame 10 of the apparatus, as will presently appear. The mandrels, together with the plugs 32, are preferably made of some metal which has a fair degree of strength and rigidity, together with lightness. For example, a suitable material is an aluminum base alloy containing copper.

The frame 10 includes an elongated side member 33, which can be conveniently made of sheet metal bent channel shaped to form a pair of flanged portions 34. A handle 36, made of suitable material such as a phenolic condensate product, is mounted upon one end of side frame member 33. Mounted upon the other end of side frame member 33, there is a suitable clamping device 37 adapted to grip a strand of hair adjacent the scalp.

With respect to the details illustrated for the clamping device, a pair of plates 38 are mounted upon the end of side frame member 33. A pair of relatively rigid bars 39 are fixed to plates 38, and extend substantially at right angles to side frame member 33. Another pair of bars 41 are pivotally connected to plates 38 as by pivot pin 42. A link 43 is connected to the free end of bars 39 by pivot pin 44. The free ends of bars 41 are formed hook shaped as indicated at 46, and are adapted to be engaged by a cam 47, formed upon a cam lever 48. Cam lever 48 is connected to link 43 by pivot pin 49. Tubular members 51 and 52, of resilient material, as for example soft vulcanized rubber, are positioned upon bars 39 and 41. When members 51 and 52 are forced together upon a hair strand, cam portion 47 can be engaged with hook portions 46, and by rotating lever 48 to a position illustrated in Fig. 6, members 51 and 52 can be firmly clamped together and locked in such position. Note that the general plane of clamp-

ing device 37, as shown in Figs. 1 and 2, is at an angle of less than 90° with respect to the plane of frame 10.

The mounting between the mandrel-like forms and the frame 10, is preferably such that a certain amount of self aligning movement of each form is permitted, and also such as to permit the individual forms to slide longitudinally with respect to the frame. The detailed construction illustrated in Figs. 3 to 5 inclusive, consists in forming the flanges 34 of side member 33 with beaded or turned edge portions 54. The adjacent ends of the mandrel-like forms including the plugs 32, are provided with key hole shaped slots 56, to accommodate the beaded edge portions 54 and flanges 34. This interlocked connection with the frame serves to retain the axes of the mandrel-like forms generally parallel, but sufficient tolerance is afforded to permit sliding movement upon side frame member 33. Likewise since each slot is relieved as indicated at 55 (Fig. 5), limited self aligning movement is permitted in a direction lateral to the axis of each form, and substantially parallel to the planes of the axes of form groups 11 to 17 inclusive and 21 to 27 inclusive.

It will be noted from Fig. 1 that the mandrel-like forms 11 and 21 are adapted to engage the resilient members 51 and 52 of the clamping device 37. Thus when all of the mandrel-like forms are urged toward clamping device 37, the forms 11 to 17 inclusive take the position in which their axes are offset with respect to the axes of forms 21 to 27 inclusive. The amount of this offset, when the sides of each row or group of forms are in contact, is equal to substantially one-half the distance between the axes of adjacent forms. In other words as the apparatus is viewed in Fig. 7, the line of contact between two adjacent upper mandrel-like forms is directly above the axis of a lower form.

In order to yieldably urge all of the mandrel-like forms together, and towards clamping device 37, I provide a presser device 58. This device can conveniently be formed of a sheet metal member 59, bent to form side finger hold portions 61 and 62, and portions 63 and 64 adapted to abut the sides of the adjacent mandrel-like forms 17 and 27. Member 59 is mounted upon a rod 66, which in turn is slidably disposed within a bore 67 formed in handle 36. A compression spring 68 serves to yieldably urge presser member 58 towards the clamping device 37, so that all of the mandrel-like forms are normally urged together in a direction laterally with respect to their axes. One side of member 59 is shown guided upon frame member 33, and the other side can be guided by a strip 69, which slidably engages the channel shaped member 71.

A suitable device for heating the hair strand retained by the mandrel-like forms of my apparatus is illustrated in Figs. 10 to 15 inclusive. This device or heater consists of a pair of relatively flat opposed members 73 and 74, which may be in the form of metal plates. Plates 73 and 74 are mounted on elongated rigid casings 76 and 77, which serve to enclose electrical heating elements. The ends of casings 76 and 77 are mounted upon handles 78, which have inwardly projecting tabs 79 connected together by pivot pins 81. A suitable spring 82, associated with handle 78, serves to urge members 73 and 74 towards each other. The conductors of a flexible electrical cord 83, serve to make electrical connection with the heating elements contained in casings 76 and 77. By pressing manually upon

the projecting portions of handles 18, it is evident that members 13 and 14 can be forced apart. Plates 13 and 14 are of ample width and length to encompass the exposed sides of the mandrel-like forms. When in position to heat a hair strand, the heater is placed over the apparatus previously described, in the manner shown in Fig. 11. When current is then applied to the heating element, heat is transferred from plates 10 13 and 14, to the hair strand and likewise to the mandrel-like forms.

When sufficient heat is applied to the strand to render the wave permanent, it is desirable to have some form of pad positioned upon the inner sides of plates 13 and 14, to retain various vaporizable solutions such as are commonly used in permanent waving. Thus, in Figs. 11 and 12 I have shown suitable pads 86 of absorbent material such as cotton flannel, interposed between plates 20 13 and 14 and the sides of the mandrel-like forms. These pads are preferably provided with a backing 87 of parchment paper or like material, the edges of which can be sewed to the flannel portion of the pad as indicated at 90. 25 To retain these pads upon the heater, while the heater is being applied, I have shown each of plates 13 and 14 provided with projecting teeth 88 upon which the parchment backing of the pad can be engaged. I also preferably provide each 30 of the pads with one or more apertures 89, as shown in Fig. 14. When the pads are in position upon the heater, these apertures accommodate bosses 91, formed of non-metallic material such as phenolic condensate product, and which project from the inner faces of plates 13 and 14. 35 Bosses 91 not only aid in retaining the pads in proper position, but also facilitate escapement of steam and vapors during the heating operation.

It is generally most convenient to insert and 40 remove the heater in a longitudinal direction with respect to the frame 10 of the waving apparatus. In this connection it is generally desirable to support the main part of the waving apparatus, previously described, by a cord 92 (Fig. 11) having 45 its lower end connected to handle 36 and having its upper end connected to a suitable reel or other counterbalancing device. The heater can be provided with a member 93 apertured to receive cord 92, so that in applying the heater it 50 is slid downwardly and over frame 10, and to effect removal it is slid upwardly upon cord 92.

In Fig. 9 I have illustrated a suitable tool 95 to facilitate arranging a hair strand upon the mandrel-like form. This tool consists of a relatively flat blade 96, formed of suitable material such as metal, and secured to a handle 97. One edge of blade 96 is provided with projecting spaced tabs 98, to form a hair receiving slot 99.

In manipulating my apparatus, the operator 60 first segregates a flat hair strand from the head of hair, such as indicated by numeral 9 in Figs. 1 and 7. This strand is then engaged at a point adjacent the scalp by the clamping device 37. The projecting strand of hair is then combed 65 out flat, and is permitted to extend along the outer side of forms 11 to 17 inclusive. The operator now steadies frame 10, and then forces the blade 96 of tool 95 downwardly between forms 11 and 12. During this operation tabs 98 are of 70 course advanced foremost and since these tabs are at opposite edges of the strand of hair, the strand is received in slot 99. As the blade of the tool is thus advanced forms 11 and 12 move apart a certain amount, such movement being accommodated by movement of the presser device 58

against spring 68. The blade of the tool is twisted in such a manner that it passes between form 21 and member 51 of the clamping device 37.

As the blade of the tool is passed between the forms in the manner just described, it is evident 5 that the strand of hair is doubled and carried first between forms 11 and 12, and then between form 21 and member 51. After all of the blade of the tool has cleared form 21 and member 51, continued movement in the same direction serves 10 to carry through all of the remainder of the strand. The operator then again engages the strand with the blade 96, and then forces the blade between forms 21 and 22 and between forms 11 and 12. Continued movement of the 15 blade in this direction then carries through all of the hair strand to the side of the apparatus upon which forms 11 to 17 are positioned. The flat strand of hair has now been looped about the periphery of form 11, and has also been looped, 20 but in a reverse direction, about form 21. The next operation is to carry the remaining portion of the hair strand between forms 12 and 13, and forms 21 and 22. This serves to form another 25 loop about the periphery of form 12, and this loop is then in a reverse direction with respect to the loop on form 21. Successive operations of the same character as described above serve to place the entire hair strand upon the forms, preparatory to the heating or cooking operation. 30

The operation just described can be better understood by reference to Figs. 16 to 18 inclusive, in which arrow 1 represents the blade of tool 95. The dotted lines of these views show the progression of the strand as it is being placed between 35 and upon the forms.

In connection with the above described manner of applying a hair strand to the mandrel-like forms it should be noted that during these operations the hair strand is placed under tension as 40 it is looped. This is by virtue of the fact that the forms are always being urged together by means of the presser device 58, which causes the forms to be pressed against the sides of blade 96 as this blade is being passed through the apparatus. 45 Likewise this tension is retained, as the side portions of adjacent loops are pressed together between the adjacent side portions of the forms.

To heat the hair strand after it has been arranged upon the forms, pads 86 are applied to 50 the heater and saturated with a suitable vaporizable solution, and then the heater is applied over the forms in the manner illustrated in Fig. 11. Heat is applied directly to the portions of the strand which are in contact with the pads and 55 also to the remainder of the strand by virtue of transfer of heat to the metal forms. When the heating operation has been completed, and the heater removed, the operator retracts the presser member 58, the clamping device 37 is released, 60 and the tip of the strand then pulled towards the ends of the forms which are unsupported. Since retraction of the presser device 58 relieves the force tending to urge the forms together, the strand readily frees itself from the forms. 65

In the manufacture and use of commercial machines incorporating my apparatus, I utilize a plurality a waving units, so that an entire head of hair can be waved in a single operation. The number of mandrel-like forms incorporated in 70 each unit depends upon the length of hair to be waved. In general apparatus designed for taking a relatively long strand of hair, can be operated successfully on shorter strands, although with apparatus which is to be employed permanently 75

for short strands, a large number of forms involve needless expense and unnecessary parts.

In addition to the novel characteristics of my apparatus previously described, it may be pointed out that the steps necessary for applying a strand to the apparatus can be readily mastered by an operator, and can be carried out in a minimum of time. No stretching or severe tensioning of the hair strand is involved and thus the apparatus can be employed without deleterious effect to the hair, and with a maximum of comfort to the subject. No great amount of tensioning is required for the reason that the tension employed is uniformly distributed throughout the strand and to the separate hairs. A relatively short heating period is required to make the wave permanent and relatively high temperatures need not be employed. This is for the reason that the heat need penetrate only a single thin layer of hair and because the major portion of the periphery of each form is in contact with the hair. This last mentioned characteristic likewise avoids deleterious effect upon the hair and the subject does not experience undue heating effects. The wave produced from my apparatus is natural and like-like in appearance. The ultimate wave produced is of course not of the shape in which the strand is arranged upon the apparatus, but is of marcel character. It may be noted in this connection that upon removing the strand from the apparatus, it is turned through an angle of 90° to lie flat upon the head.

I claim:

1. In hair waving apparatus, means for retain-

ing a hair strand in the form of a plurality of connected loops with adjacent successive loops reversely flexed, said means comprising a plurality of elongated mandrel-like forms, a pair of members adapted to engage opposite sides of said forms and adapted to be heated, pads of absorbent material adapted to be inserted between said members and said means, said pads being apertured, and bosses formed on the inner faces of said members and adapted to be received in the apertures of said pads.

2. In a hair waving apparatus, a frame, two rows of mandrel-like forms slidably secured to said frame, the axes of the forms in each row being generally parallel to the axes of the other forms in the row, and spring means for urging said forms of each row together in a direction laterally with respect to their axes, whereby said forms can be forced apart against said spring means in the winding of a hair strand.

3. In a hair waving apparatus, a frame, said frame including a substantially linear side member, a plurality of mandrel-like forms having their axes arranged generally parallel, means for mounting one end portion of each of said forms upon said frame for sliding movement longitudinal of the frame and for affording limiting self aligning movement between each form and the frame, and spring means mounted adjacent one end of the frame and serving to urge all of said forms together in a direction laterally with respect to their axes.

RALPH M. KEELE.
